UNITED STATES PATENT OFFICE.

MICHAEL NIELSEN AND THOMAS S. THOMSEN, OF GREENWICH, CONNECTICUT, ASSIGNORS OF ONE-THIRD TO MARTIN BARIFFI, OF PORT CHESTER, NEW YORK.

DESIGN FOR A KNIFE-SHARPENING JAW.

SPECIFICATION forming part of Design No. 28,066, dated December 21, 1897.

Application filed November 8, 1897. Serial No. 657,884. Term of patent 7 years.

To all whom it may concern:

Be it known that we, MICHAEL NIELSEN and THOMAS S. THOMSEN, citizens of the United States, residing at Greenwich, in the county of Fairfield and State of Connecticut, have invented and produced a new and original Design for a Knife-Sharpening Jaw, of which the following is a specification, reference being had to the accompanying drawings, forming a part thereof, in which—

Figure 1 is a perspective view of a knife-sharpening jaw embodying the features of our design, and Fig. 2 is a vertical section of the jaw.

The design consists in the shape of the jaw and in the formation of its peripheral surface, which presents a series of annular steps, each step having a flat surface α and a tapering surface α' , connecting with the flat surface.

We claim—

The design for a knife-sharpening jaw herein shown and described.

MICHAEL NIELSEN.
THOMAS S. THOMSEN.
